UNITED STATES PATENT OFFICE.

FREDERICK A. HART, OF NEW BRITAIN, CONNECTICUT, ASSIGNOR TO REMINGTON TYPEWRITER COMPANY, OF ILION, NEW YORK, A CORPORATION OF NEW YORK.

TYPEWRITING MACHINE.

Application filed May 24, 1927. Serial No. 193,872.

My invention relates to typewriting and like machines, and it has for its principal object to provide certain improvements in power-operated carriage return mechanism 5 for such machines. To that end my invention consists in certain features of construction and combinations and arrangements of parts, all of which will be fully set forth herein and particularly pointed out in the claims.

10 In the drawings the improvements are shown applied to the carriage return mechanism which has heretofore been employed in the Remington typewriter, which mechanism is shown well enough for the purposes of this 15 case in my prior Patent No. 1,567,590, dated December 29, 1925, and in my application Sr. No. 127,324, filed August 5, 1926. The Remington mechanism being well known on the market, and being substantially shown in the 20 two cases referred to, I have illustrated in the drawing only such parts thereof as are thought necessary to an understanding of the present improvements.

One object had in mind in the present invention 25 has been better to adapt the mechanism for use on ordinary correspondence typewriters having comparatively narrow and light carriages. The mechanism shown in my prior patent was adapted for wide carriages loaded with adding mechanism, and while it could be used to advantage in lighter machines, it contained mechanism that could be dispensed with or simplified in a machine with a light carriage; and the carriage return 30 mechanism shown in the drawing is accordingly simpler in some respects than that shown in any prior cases.

In my prior patent the usual line lock mechanism of the typewriter is dispensed 40 with and the right-hand margin stop on the carriage is used to start the carriage return mechanism. In ordinary correspondence typewriters, an automatic starting device for the carriage return mechanism is not usually 45 desirable and in most instances I omit it. It is sometimes wanted, however, and I accordingly provide for its use but have modified it in such a way that it does not interfere with the usual line lock mechanism, which mechanism I retain in the typewriter and utilize it 50 as part of the carriage starting mechanism when the latter is required.

When a user of this sort of typewriter does 55 wish an automatic starter for the carriage return mechanism it is frequently the case that

he wishes that mechanism only on certain classes of work and does not desire it on other classes of work. I have accordingly put in a disabling device so that by an almost instantaneous hand operation the automatic starter 60 can be rendered operative or inoperative, as desired.

One form of my invention is illustrated in the accompanying drawings all of which are fragmentary in character and show some 65 parts of the machine more or less conventionally.

Fig. 1 is a front view of the left-hand portion of the machine, partly in section.

Fig. 2 is a similar view of the right-hand 70 portion of the machine.

Fig. 3 is a plan view showing the middle of the carriage.

Fig. 4 is a section on the line 4—4 of Fig. 1 and looking towards the right.

Fig. 5 is a left-hand side elevation with the cover plate of the control box removed.

Fig. 6 is an enlarged sectional view of a disabling device.

In said drawings, 5 is the base of the typewriter frame, 6 the corner posts, 7 the top plate, 8 and 10 the front and rear stationary carriage rails, and 11 is the carriage truck including the front bar or rail 12. 13 represents the roller bearings of the carriage, 14 the usual left-hand margin stop, and 15 the usual right-hand margin stop both adjustable in the ordinary way along bars 16 rigid with the front rail 12 of the carriage. The carriage is fed leftward by the usual spring drum and controlled by the usual escapement and other feed mechanism of which none is shown in the drawing, except the feed rack 17 which is pivoted to the carriage at 18. The tabulator mechanism comprises a column stop bar 20 mounted on the carriage by brackets 21 and carrying column stops 22 which are acted on by stop mechanism conventionally represented at 23. This may be the mechanism described in the application of George A. Seib, filed May 13, 1925, Sr. No. 29,874, and need not be further described except to say that it is operated by a tabulator key 24 whose key lever 25 pulls down on a link 26 which throws the stop included in mechanism 23 into the path of the column stops 22 and which by means of a lifter 27 raises the feed rack 17 out of engagement with the feed pinion.

The line lock mechanism may be similar to 110

and except for a detail hereinafter pointed out may be identical with that shown in the patent to Seib No. 1,345,894, dated July 6, 1920. It includes a flanged plate 28 pivoted 5 in the base 5 at 30 and adapted to have its lower flanged edge swung rearward under hooks on the printing key levers so as to lock them. This swinging is effected by a link 31 pivoted to the piece 28 forward of its pivot 10 and extending upward through or behind one of the posts 6 and through the top plate above which it is pivoted to a bell crank 32, which bell crank is controlled by sliding a plate 33 mounted to slide underneath the stationary 15 rail 8. At the middle of the machine, this rail has fastened to it by two screws a sort of block or barrel 34 having a bore 35 in which a plunger can slide lengthwise right and left, and can also rock about its axis. The middle 20 part of the barrel 34 is cut away as shown and described in the Seib patent and in this cut-out a block 36 is fastened to said plunger so as to slide and rock therewith. Said block 36 extends upward and rearward into the 25 path of the margin stops 14 and 15. A sheet metal piece 37 is fastened to the block 36 and extends downward and forward to constitute a carriage release key. By pressing down on this piece, the stop mechanism can be rocked 30 about the axis of the plunger so as to bring the stop block 36 out of the path of the margin stops. The cut-out in the barrel 34 is a little wider than the block 36 so as to allow a limited sliding motion to said block, which 35 block normally occupies its right-hand position whence it can be slid a short distance leftward by the margin stop 15 with the result of rocking the plate 28 and locking the keys. This whole mechanism contains a number 40 of details which are not shown in the present drawings but which are shown in the Seib patent and which are well known in the art. I have made only two changes in this mechanism, namely, I have trimmed off the 45 left-hand portion of the finger piece 37 so as to give said piece a straight left-hand edge; and I have slightly modified the means for fastening the block 34 to the rail 8.

The carriage return mechanism heretofore 50 employed comprises an electric motor 40 whose shaft is connected by a flexible connection 41 with a horizontal shaft geared at its forward end by beveled gears 42, 43 with a clutch section 44 loose on a vertical drive 55 shaft 45 having at its upper end a drive pinion 46 meshing with a rack 47 mounted on the under side of the rear bar 48 of the carriage. The rack 47 is mounted on the bar 48 by pin and slot connections allowing to said rack a 60 preliminary motion to effect line spacing. All of the mechanism from the motor 40 to the pinion 46, as well as other parts, are mounted as a unit or sub-assembly in a casting 50 secured to the base plate 5 and top 65 plate 7 of the typewriter.

The clutch section 44 is mated by a clutch section 51 splined on the shaft 45 and controlled as to its engagement and disengagement by a roller or pin 52 projecting from an arm 53 fast on a transverse rock shaft 54 pivoted near its right-hand end in the casting 50 and pivoted near its left-hand end in an ear 55 of a control-box 56 secured by three screws 57 to the left-hand side of the typewriter frame. The arm 53 is integral with a depending arm 58 to which is pivoted a push rod 60 having on its a spring 61 which tends to rock the shaft 54 so to throw the clutch section 51 into engagement. The rod 60 at its rear end controls the switch of the electric motor, opening said switch when the rod moves rearward.

In order to hold the shaft 54 and the parts connected therewith in their normal positions against the pressure of the spring 61, said shaft has an arm 62 mounted on the left-hand end thereof and projecting into the control-box 56 where it is normally held down by a latch or detent 63 pivoted on a stud 64 projecting from the wall of the box. In the present instance the said stud is prolonged and it has a collar 65 mounted on it and secured by a set screw to retain the latch against displacement.

The latch 63 may be operated to release the arm 62 by means of a hook 66 normally in position to engage a pin 67 projecting from the latch, said hook at its forward end being pivoted at 68 to a lever arm 70 mounted on a transverse rock shaft 71 which extends through the machine and has a starting key 72 mounted on its right-hand end and lying at the right of the typewriter keyboard. There are some devices in the train of connections from the key 72 to the hook 66 which are not shown in the present instance but which are shown in my patent above referred to. A spring 73 connected to the latch 63 and hook 66 serves to return them both to normal position. In the present instance a lug 74 is 100 cast on the bottom or wall of the box 56 and has a slot 75 cut therein to serve as a guide for the hook 66 and another part.

In some instances contemplated by the present invention no automatic starter is used and in that event the lever arm 70 may be merely an arm fast on the shaft 71. In other instances the machine may be equipped with an automatic starter and in that case the arm 70 is made with a branch 76 projecting forward through a suitable hole 77 in the box 56; and said arm is loose on the shaft 71. In that event an arm 78 is fastened on the shaft 71 and is provided with a pin 80 for operating the lever arm 70 in the same manner as in my prior patent.

The mechanism at the front of the carriage and at the middle of the machine has been modified in the present instance. The block 34 is counter-bored from the front to 130

receive two sleeves 81, Fig. 4, one surrounding each of the screws 82 by which the parts are fastened to the rail 8. A sheet metal casting 83 is pierced in front with holes the size 5 of the screws 82 which pass through said holes and clamp the casing 83 between the screw heads and the outer ends of the sleeves 81, thus rigidly fastening said casing in place, and at the same time through the sleeves 81 10 rigidly securing the block 84 to the rail. A pull rod 84 passes through a hole in the left-hand wall of the casing 83 and has its right-hand end bent rearward at an upward inclination to form an abutment or stop piece 85 lying in the path of the left-hand margin stop 14 on the carriage. In the normal position of the parts the abutment 85 is something like half an inch to the left of the stop block 36, 37 so that when the carriage 15 20 is drawn back to the right the stop 14 will strike abutment 85 and draw it rightward until both they and the carriage are arrested by the abutment 85 striking against the stop block 36, 37. Except for the details above 25 described the rod 84 is similar to a rod formerly used and shown in my prior patent and application. At its left-hand end it is pivoted at 86 to a bell crank 87 which is pivoted on a shaft 88 mounted in a bracket 30 35 40 45 50 55 60 65 70 75 80 85 90 95 100 105 110 115 120 125 130 90 which is mounted on the top plate 7 of the typewriter. The horizontal arm of the bell crank 87 is pivoted at 91 to a vertical link 92 which at its lower end is pivoted at 93 to a bell crank 94 which is pivoted on a stud 95 projecting leftward from the bottom of the box 56. The other arm of the bell crank 94 is pivoted at 96 to a bar 97 which at its rear end has a slot 98 by which it is guided on a stud 100 projecting from the floor of the box 56. The bar 97 is further guided by a flanged roller 101 journaled on a stud 102. Said bar is formed on its lower edge with a cam part 103 followed by a dwell 104, said cam and dwell for cooperation with a roller 105 journaled at 106 on the arm 62. The whole construction is such that when in the last part of the return motion of the carriage the stop 14 operates the abutment 85, the cam 103 engaging the roller 105 will depress the arm 62 and disconnect the clutch 51, 44, and break the circuit through the motor. The arm 62 will be caught by the latch 63. Said latch is preferably made with a main hook portion 107 and above that with a series of very fine ratchet teeth 108, which latter will catch the arm 62 in case the carriage does not have quite momentum enough to depress said arm to its fullest extent. The advantage of this mode of operation is set forth in my application above referred to. In practice the teeth 108 are finer than shown in the drawing.

In my prior application it is explained 65 that it is not desirable that the latch 63 ever

be operated to release the arm 62 while the cam 103 and dwell 104 are either in contact with or within a certain distance of the roller 105; in other words, this latch should not be tripped until after the carriage has traveled several letter spaces leftward from its extreme right-hand position. The present drawings show the same means for preventing this as my said prior application, namely, a pin 110 eccentrically mounted in the bar 79 84 and underlying the hook 66, in such position that said pin holds the hook 66 up in operative position when the bar 97 is in normal position as shown in the drawings, but when said bar is displaced slightly forward and downward from normal position this supporting pin is removed from the hook 66, allowing the latter to drop down to a point where it will not engage the pin 67.

The train of mechanism including the bar 85 97, bell crank 94, etc., is provided with a returning spring 111 which in the present instance is coiled about the hub of the bell crank 94, one end of the spring engaging said bell crank and the other a fixed part. 90

In my former construction a good sized dash-pot was located in the lower rear corner of the control-box 56 and there was a train of mechanism for operating said dash-pot and for connecting it with and disconnecting it from its operating mechanism. 95

All of these parts are omitted in the present instance which considerably simplifies the mechanism and enables me to make the control box thinner in a right and left hand direction. Said control-box is provided with a cover plate 112, Fig. 1, secured thereto by two screws at 113, Fig. 5. In the present instance, I utilize this cover plate as a housing for a rheostat. To this end, said cover plate 100 105 is made with a circular barrel-shaped portion 114 which is covered by a cap 115. The stationary parts of the rheostat are in the barrel 114 and the movable parts thereof are connected with the cap 115, which is so mounted as to enable it to be turned by hand to different settings indicated visually by graduations 116 on the cap 115, registering with an index 117 on the barrel 114. Two conductor posts 118 included in the motor circuit are shown mounted on a piece of insulating material 119 and projecting through a suitable hole 120 in the floor of the control-box. The rheostat has two spring contacts 115 120 125 in such position relative to the cover plate 112 that when the latter is in place they bear on the posts 118 and thus put the rheostat into the circuit. The machine is connected up with the house circuit and the rheostat is adjusted to give the right degree of power to the motor. If the carriage goes back too violently additional resistance is thrown into the circuit and if it does not go back with sufficient energy the resistance is diminished.

With light carriages, I find that the rapidity 130

of the return of the carriage can be regulated well enough in this way so as to dispense with the dash-pot altogether. In some instances, I may use the pneumatic governor 5 described in my prior patent but in most instances this also can be dispensed with.

The mechanism already described is all that is necessary unless the user of the machine has some work for it to do in which 10 an automatic return of the carriage at the end of the line is desirable. The machine is so designed that this automatic return can be provided and it is shown in the drawing. In other words, the machine is so designed that 15 the automatic starter for the carriage return can be put in or left out as desired.

It has already been pointed out that if no automatic return is wanted the arm 70 would be rigidly mounted on the shaft 71 and the 20 parts 76, 78 and 80 would be omitted. When the automatic return is wanted, the arm 76 is provided and is pivoted at 121 to the lower end of a push rod which is made in two sections, namely, a lower section 122 and an up- 25 per section 123, the latter pivoted at 124 to a lever arm 125 secured to the rear end of the shaft 88 hereinbefore referred to. At its forward end, said shaft has secured thereto a lever arm 126 which is pivoted at 127 to a 30 horizontal push rod 128 which at its right-hand end passes loosely through a hole in the left-hand wall of the sheet metal casing 83. This rod terminates as shown in Figs. 1 and 4 substantially in contact with the left- 35 hand edge of the part 37 which I have made straight for that purpose. The whole construction is such that when the carriage reaches the end of its leftward travel and the block 36, 37 is slid leftward to operate the 40 line lock, said block will push the rod 128 leftward and depress the arm 76 and thus operate the hook 66 to set the carriage return mechanism into operation. In case the automatic return is not desired, a plain shaft 88 45 is inserted in the bracket 90 to serve as a pivot for the bell crank 87 and suitable means are provided to prevent the shaft from coming out of the bracket.

An automatic carriage return brought into 50 action by the arrival of the carriage at the end of a line is usually considered to be useful only on that class of work such as tabulating work where the line always ends at the same letter-space position, in which event 55 it is a considerable advantage. Wherever the machine is used for ordinary writing such as correspondence work, the automatic starter not only is not necessary but it may even be a disadvantage. The line lock may be thrown 60 into operation in the middle of a syllable, in which event the operator desires to depress the release key 37 and allow a few more steps to the carriage to finish the syllable and it would be a disadvantage if the carriage return mechanism started into operation the 65

instant the line lock was operated. On machines of the lighter sort or size for which my present invention is more particularly designed correspondence work or ordinary writing is likely to be done at times even 70 if the user of the machine also has tabulated work to do at other times. As it is desirable to have the automatic return used on the tabulator work and to have it out of use when ordinary writing is to be done, I have provided means for disabling this mechanism and it is for this reason that the push rods 122, 123 is made in two sections. Said two sections enter loosely the lower and upper ends respectively of a vertical bore in a barrel or 80 block 130 which also has a cross bore in which is situated a horizontal shaft 131 having on its forward end a cross piece 132 by means of which it can be turned. In line with the rods 122, 123 the shaft 131 is made with two 85 opposite cut-outs leaving between them a comparatively thin wall 133, Fig. 6. The construction is such that when the shaft 131 is turned to the position shown in Fig. 6, the block 130 can drop down until the flat lower 90 surface of the wall 133 rests on top of the rod 122. This leaves the lower end of rod 123 some distance above the upper surface of the wall 133, as shown in Fig. 6, so that even if the line lock be operated, resulting in pushing downward on the rod 123, such downward motion will not be communicated to the rod 122 and will not start the carriage return mechanism. If, however, the shaft 131 be given a quarter turn by means of the cross 95 piece 132 the full width of the shaft 131 will then stand between the ends of the rods 122, 123. The turning of the shaft will by cam action move the block 130 slightly upward so that the rod 123 will be substantially in contact with the shaft 131 on the upper side and the rod 122 will be in contact with it on the lower side. If now the line lock be operated 100 the downward motion of the rod 123 will be communicated to the rod 122 and the carriage 105 will be automatically returned.

In order to assist in controlling the shaft 131 the latter is provided with a cross pin 134 adapted to enter notches 135 made at 90 degrees apart in the hub portion of the block 130 where the rear end of the shaft 131 projects therefrom. A compression spring 136 is seated in a counterbore in the forward hub-like part of the block 130 and acts on a shoulder or flange 137 made by the enlarged forward end of the shaft 131. This spring holds the pin 134 seated in the notches 135. There are four of these notches and they hold the shaft in any suitable position to which it may be turned.

In order to prevent the block 130 from turning around on the rods 122, 123 one of said rods, for example, rod 122, is made with a longitudinal cut or slot 138 and a cross pin 140 is inserted through the block 130 as 130

shown in Fig. 6. The rod 122 can be inserted in the block only in such positions that the pin 140 enters the slot 138 and the block can not turn on the rod. It will be understood 5 that if either rod section 122 or 123 be disconnected it can be immediately removed from the block 130 which can then be slid off the other rod section and removed. But as long as both rod sections are connected up, the 10 block can not become displaced. These rod sections are adjustable as to length in the ordinary way so as to get the right action in releasing the latch 63.

In my prior Patent No. 1,609,943, dated 15 Dec. 7, 1926, I have shown means for preventing the carriage return mechanism from being operated during the time when a tabulator key was being operated. In the present instance means are provided for the same 20 purpose, these consisting of an arm 141 mounted by means of a split clamping hub 142 on the rock shaft 54 in position to be depressed by a pin 143 projecting from the pull link 26 of the tabulator mechanism shown in the 25 present instance. The construction is such that if the tabulator key 24 be depressed while the carriage return mechanism is in operation, the pin 143 will rock the shaft 54 and open the clutch 44, 51 and open the circuit 30 through the motor. If, on the other hand, the tabulator key is in its depressed position when the carriage return mechanism would otherwise come into operation, the pin 143 will prevent the backward rotation of the 35 shaft 54 and prevent the carriage return mechanism from acting until the tabulator key is released. For example, if the tabulator key was depressed after the last column stop 22 had passed the stop device 23, then the 40 carriage would run to its extreme left-hand position and the action of the margin stop 15 on the line lock mechanism would tend to start the motor into operation and draw the carriage back, causing it to be arrested by the 45 tabulator mechanism on its return motion. This will be prevented by the interlocking device just described.

Various changes may be made in the details of construction and arrangement without departing from the invention. 50

What I claim as new and desire to secure by Letters Patent, is:—

1. The combination with a step by step moving carriage, a motor for returning the carriage, a key for bringing said motor into action, line lock mechanism acting at the end of a line and including line lock releasing means to enable the carriage to take additional steps, and an automatic starting device capable of 55 bringing the returning motor into action automatically at the end of a line, of means for enabling and disabling said automatic starting device but not affecting the operativeness of said key to cause a return of the carriage, 60 said means settable to enabling and to dis-

abling condition and retaining its setting so that the automatic starting device can be made operative on one piece of work where it is desired and inoperative on another piece of work where it is not desired to be used. 70

2. The combination with a step by step moving carriage, a motor for returning said carriage, and line lock mechanism including a part at the front of the machine arranged to be displaced leftward by said carriage at 75 the end of a line, of a casing surrounding said part of the line lock mechanism, a push rod guided in said casing and actuated by said part, and means operated by said push rod for bringing said motor into action to return 80 the carriage.

3. The combination with a step by step moving carriage, link lock mechanism including a device at the front of the machine arranged to be displaced leftward by said carriage at the end of a line, and a motor for returning said carriage, of a casing surrounding said part, a rod guided in said casing, and means operated by said rod for bringing said motor into action to return the carriage, a 85 second rod guided in said casing, a stop on the carriage adapted to engage said second rod and draw it rightward until arrested, and means operated by said second rod for throwing the motor out of action. 90

4. The combination with a step by step moving carriage, a motor for returning said carriage, and a device which when operated brings said motor into action, of automatic means for operating said device, said automatic means including a rod made in two sections, and an interponent between said two sections, said interponent being shiftable by hand so as in one position to leave lost motion between said two sections whereby the motion of one section will not be transmitted to the other and the automatic starting mechanism will therefore be inoperative, and in the other position of said shiftable device the lost motion will be taken up so as to render the automatic starting device operative. 100

5. Automatic starting mechanism for carriage return mechanism including a rod made in two sections, and a piece interposed between said two sections and shiftable by hand to two positions in one of which positions said piece does and in the other of which it does not fill the space between the two rod sections so that in the first case the automatic return mechanism will be operative and in the second case it will be inoperative. 115

6. Automatic starting mechanism for carriage return mechanism comprising a rod made in two sections, a housing in which said two sections are inserted and a hand rotatable piece in said housing thinner in one direction than in the other, said piece when turned so as to put its thin diameter between the two rod sections rendering the automatic starting device inoperative and rendering said device 120 125 130

operative when said piece is turned to bring its thick diameter between the two rod sections.

7. Automatic starting mechanism for carriage return mechanism including two rods 120 and 123, a barrel or housing 130, and a hand rotatable piece 131 placed in said barrel across said rod sections and cut away so that when said piece is turned to one position it will and when turned to another position it will not serve to communicate motion from one of said rod sections to the other.

8. Automatic starting mechanism for carriage return mechanism including two rods

120 and 123, a barrel or housing 130, and a hand rotatable piece 131 placed in said barrel across said rod sections and cut away so that when said piece is turned to one position it will and when turned to another position it will not serve to communicate motion from one of said rod sections to the other, and means to prevent said barrel from turning on said rod sections.

Signed at the borough of Manhattan, city of New York, in the county of New York and State of New York, this 23rd day of May, A. D. 1927.

FREDERICK A. HART.
